Primary Examiner—Ruth McInroy*Attorney, Agent, or Firm*—Brooks & Kushman[57] **CLAIM**

The ornamental design for a portable vacuum cleaner, as shown and described.

DESCRIPTION

FIG. 1 is a perspective view of a portable vacuum cleaner showing our new design;

FIG. 2 is a left side elevational view thereof;

FIG. 3 is a front elevational view thereof;

FIG. 4 is a right side elevational view thereof;

FIG. 5 is a top plan view thereof;

FIG. 6 is a rear elevational view thereof; and,

FIG. 7 is a bottom plan view thereof.

The electric cord shown broken away in FIGS. 1, 2 and 4-7 is understood to represent indeterminate length.
